UNITED STATES PATENT OFFICE.

ALBANUS W. MORTON, OF RAHWAY, NEW JERSEY.

IMPROVEMENT IN GAS-STOVES.

Specification forming part of Letters Patent No. 173,985, dated February 22, 1876; application filed January 17, 1876.

To all whom it may concern:

Be it known that I, ALBANUS W. MORTON, of Rahway, in the county of Union and State of New Jersey, have invented a new and useful Improvement in Gas-Stoves; and I do hereby declare that the following is a full, clear, and exact description of the same, reference being had to the accompanying drawing, which forms part of this specification.

My invention relates to that class of gas-stoves designed more particularly for heating apartments in dwellings. It consists in a novel construction and arrangement of flues and a heating-drum, said flues and heating-drum being arranged in relation with an annular burner, whereby a constant circulation of the air, in an apartment heated by said stove, is maintained through said drum and flues, and a very perfect combustion of the gas is secured.

In the drawing, Figures 1 and 2 are central vertical sections at right angles with each other.

Similar letters of reference refer to like parts in both figures.

S is a shell, of sheet metal or other suitable material, resting upon a suitable base, B. The shell S supports the shell S', which incloses the drum D. The said shells may be made of cylindrical or elliptical or other cross-section, cylindrical being the form I prefer. On the interior of the lower part of the shell S' are riveted or otherwise attached brackets b², upon which the annulus a, attached to the lower edge of the outer wall w¹ of the drum D, rests, the entire drum D being supported by the said brackets b². The said drum D consists of the walls w, w¹, and w². The interior wall w is conoid or pyramidal in form, the conoid form being preferred. The upper edge of the said wall w is joined, by riveting or other suitable means, to the upper edge of the wall w¹, and it is provided with openings near the top, as shown at o, which allows air to pass freely through them. The bottom wall w² is united to the bottom edge of the wall w by riveting or other suitable means. The walls w and w¹ inclose the ascending annular flue f, contracted toward the top, and the wall w¹ and the shell S' inclose the descending annular flue f¹. This descending flue f¹ commu-

nicates with the external air through openings o', arranged either in one group at the bottom, or at intervals around the bottom of the shell S', a greater or less number of openings being used, according to the size of the stove. The front part of the shell S' is cut out to leave an ample and free ingress for the air to be heated when the stove is in operation.

I prefer to place in the shell S the deflector or chute, which extends backward and upward, as shown in Fig. 2, and which directs the entering air upward, and I also prefer to make the front side of said chute or deflector polished, to reflect cheerful light and heat into the apartment, as indicated by rays r; but said chute or deflector forms no part of my invention.

Gas is admitted through a suitable pipe, P, which leads to an annular burner, b, said annular burner b being provided with apertures, preferably on the outer side, to permit the escape of the gas in an outward direction. This annular burner is concentric with the drum D, and has about the same circumference as the bottom w² of the drum D. It is supported by the pipe p, of which it, preferably, forms a continuation.

Upon the top of the shell S is either formed, or, being separately formed, is supported, a cornice, c, forming a support for the upper wall of the flue f¹, the space in which flue is continuous with the space inclosed by the drum-walls w and w². The said cover C, when placed in position, as shown in Fig. 1, forms the top wall of the flue f¹, and it renders the chamber inclosed by the drum-walls w, w¹, and w² available for heating articles needed in nurseries and sick-rooms, said articles being rested upon the bottom wall w² of the drum D.

When the gas flows through the pipe P, and is lighted at the burner b, the flame jets outward into the air at the bottom of the flue f. The air, being heated, rises, by virtue of its diminished specific gravity, and passes into the flue f, thence it issues through the aperture o into the heated space inclosed between the walls w and w²; but as it cannot descend into this space it passes upward, and is deflected by the cover C into the annular flue f², down which it is pressed by the air behind it

till, being intercepted by the annulus *a*, it issues heated into the apartment.

I claim—

1. The drum *D*, consisting of external and internal walls *w*¹ and *w*, inclosing an upwardly-contracted ascending flue, *f*, with openings *o* at the top for the passage of heated air, in combination with the external descending flue *f'*, substantially as set forth.

2. The combination, with the drum *D* and

the ascending flue *f*, of the annular burner *b*, arranged concentrically with said drum and flue, substantially as described.

3. The cover *C*, forming the upper wall of the flue *f'*, in combination with the drum *D* and the outer shell *S'*, substantially as described.

A. W. MORTON.
